DESIGN FOR A TWO-WHEEL TRAILER

Oliver W. Inskeep, Stockton, Calif., assignor to Harris Manufacturing Company, Stockton,
Calif., a corporation of California

Application November 5, 1945, Serial No. 123,443

Term of patent 14 years

(Cl. D14—3)

To all whom it may concern:

Be it known that I, Oliver W. Inskeep, a citizen of the United States, residing at Stockton, in the county of San Joaquin and State of California, have invented a new, original, and ornamental Design for a Two-Wheel Trailer, of which the accompanying is a specification, reference being had to the accompanying drawing, forming a part thereof.

Figure 1 is a side perspective view of a two-wheel trailer showing my new design; the opposite side of the trailer presenting the same appearance.

I claim:

The ornamental design for a two-wheel trailer, as shown and described.

OLIVER W. INSKEEP.
